(57) **CLAIM**

The ornamental design for an ultrasound display apparatus, as shown and described.

DESCRIPTION

The present application is related to concurrently filed and commonly assigned U.S. design patent application Ser. No. 29/268,134, entitled “Mobile Support Structure For Medical Equipment,” U.S. design patent application Ser. No. 29/268,131, entitled “Apparatus Tilt Control Dock,” U.S. patent application Ser. No. 11/590,010, entitled “Docking Station Having Auxiliary Power management For Use With Portable Medical Equipment,” and U.S. patent application Ser. 11/590,009, entitled “Adjustable Height Medical Device And Stand Therefore,” all the disclosures of which are hereby incorporated herein by reference.

FIG. 1 is an isometric view of a ultrasound display apparatus showing our new design;

FIG. 2 is a front view thereof;

FIG. 3 is a rear view thereof;

FIG. 4 is bottom view thereof;

FIG. 5 is a top view thereof;

FIG. 6 is a right side view thereof; and,

FIG. 7 is a left side view thereof.

It should be understood that the labels used herein for describing orientation (e.g., front, rear, top, bottom, right, and left) are merely for reference, and the design may be disposed in any manner and still be within the scope of the present invention. The portions of the article in broken lines are shown for illustrative purposes only and form no part of the claimed design. The portions of the article not visible in the views above form no part of the claimed design of the illustrated embodiments.

The broken line showing of the buttons, knobs, inputs, connectors and latches, is for the illustrative purposes only and forms no part of the claimed design.
